I. HELGUERA.
KEYBOARD FINGER GUIDE,
APPLICATION FILED DEC. 26, 1919.

1,377,070.

Patented May 3, 1921.

UNITED STATES PATENT OFFICE.

IGNACIO HELGUERA, OF TRENTON, NEW JERSEY.

KEYBOARD FINGER-GUIDE.

1,377,070.

Specification of Letters Patent.

Patented May 3, 1921.

Application filed December 26, 1919. Serial No. 347,290.

To all whom it may concern:

Be it known that I, IGNACIO HELGUERA, a citizen of Mexico and a resident of Trenton, in the county of Mercer and State of 5 New Jersey, have invented a new and Improved Keyboard Finger-Guide, of which the following is a full, clear, and exact description.

This invention relates to machines or instruments having manually operated keys 10 such as typewriting machines, tabulating machines, typesetting machines, or the like, in which the keys are arranged in banks or associated rows and intended to be so memo- 15 rized or mastered that it is unnecessary for the operator to look at the keys while operating the machine.

Among the objects of the invention is primarily to provide a means to enable the 20 learner to quickly and easily master the keyboard for the manipulation of a machine or instrument under what is commonly but erroneously called "the touch system." Where- 25 as by the sense of touch an operator is able to distinguish between different forms or different temperatures, the keys of a type- 30 writing machine for instance being all alike in form, feel alike and hence the sense of touch cannot be used to distinguish between any two of them. The student however 35 learns to locate or distinguish between the keys by a sense of habit acquired from knowledge of location of the various keys, and therefore one of the purposes of this im- 40 provement is to enable the learner to readily and easily coördinate his muscles in the mas- 45 tering of the location of the various keys.

With the foregoing and other objects in view the invention consists in the arrangement 40 and combination of parts hereinafter described and claimed, and while the invention is not restricted to the exact details of construction disclosed or suggested herein, still for the purpose of illustrating a practi- 45 cal embodiment thereof reference is had to the accompanying drawings, in which like reference characters designate the same parts in the several views, and in which—

Figure 1 is a plan view of a conventional 50 keyboard of a typewriting machine.

Fig. 2 is a vertical sectional view of the same on the line 2—2.

Fig. 3 is a perspective detail view of my improved finger guide.

55 While I show my improvement as applied

to a conventional typewriter keyboard it is to be understood that the principles involved are adaptable for use in connection with any other style or form of keyboard, the several keys of which are so disposed as 60 to be grouped for manipulation by predetermined fingers of the hands of the operator.

As shown my improvement comprises a series, preferably seven, of flat strips of 65 sheet material such as cardboard, celluloid, or the like, all of the strips 10 being preferably of the same size and form. Any suitable means may be provided to hold the strips or partitions 10 in proper position 70 for use and in suitable relation to one another. To this end I provide in the partitions near their lower edges and adjacent to the ends thereof remote from the operator a plurality of spaced holes 11 all of 75 which register in all of the partitions and through which supporting rods 12 are loosely threaded. Said rods may have heads or loops 13 at their ends in order to retain the partitions thereon when the de- 80 vice is disconnected from the machine. Said heads also serve to prevent undesired longitudinal sliding movement of the rods.

I show in this instance the provision of 85 seven partitions or plates 10 which are adapted to be arranged between parallel inclined rows of keys, the partitions being thus arranged at oblique angles to the axes 90 of the rods. In the manipulation of a type- writing machine it is usual to apportion to 95 the index fingers twice as many keys as to each of the other fingers, and hence the central partition is spaced from each of the partitions on either side thereof so as to group eight keys to be manipulated by each 95 of the index fingers, while each of the remaining partitions is spaced only a distance of one key from each of the succeeding partitions, thus grouping the keys in fours for all of the other fingers.

As a suitable means for supporting the partitions in position to divide the keys into predetermined groups the rods 12 may be supported directly upon the angle portions 100 of the bars 14 of the two uppermost rows of 105 keys. The remote ends of the partitions are not far from the frame 15 of the machine, and hence it is impossible for the finger guide to become displaced in this direction. After the partitions are placed as 110

- indicated it is impossible for any of them to be displaced laterally, and since the rods are engaged back of the vertical portions of the key bars there is no possibility for the guiding means to be displaced forwardly or downwardly. Since only one key is operated at a time it follows that the rods are supported at all times by all or nearly all of the key bars with which they are associated.
- 10 The width of the partitions 10 vertically is sufficient to retain the fingers properly spaced over their respective groups of keys and yet the width or height of the partitions is not enough to cause any disadvantage that might tend to interfere with the proper manipulation of the keys.
- 15 I claim:
1. In a keyboard finger guide, the combination of a plurality of spaced parallel partitions, each partition having a pair of spaced holes therethrough and a pair of sup-

porting rods loosely threaded through the holes of all of the partitions whereby the partitions may be disposed at oblique angles 25 to the axes of the rods, and means to prevent separation of the partitions from the rods.

2. The combination with a typewriter having keys supported upon angular bars 30 of a pair of rods supported on said bars, partitions carried by the rods and said partitions arranged to selectively separate rows of keys.

3. The combination with a typewriter 35 having angular keys supporting bars arranged in rows of a pair of parallel rods, resting on certain of said rows of bars, parallel partitions carried by the rods and disposed at oblique angles thereto, said partitions selectively dividing the keyboard into 40 rows of keys.

IGNACIO HELGUERIA.
